US00D566798S

(12) **United States Design Patent** (10) **Patent No.:** **US D566,798 S**
(45) **Date of Patent:** ** *Apr. 15, 2008

(54) **EXERCISE DEVICE**

(75) Inventors: **Ryan R. Dibble**, Denver, CO (US);
Patrick A. Warner, Boulder, CO (US);
Eric D. Golesh, Arvada, CO (US);
Brent Christopher, Denver, CO (US);
Edward L. Flick, Portland, OR (US)

(73) Assignee: **Nautilus, Inc.**, Vancouver, WA (US)

(**) Term: **14 Years**

(21) Appl. No.: **29/247,399**

(22) Filed: **Jun. 15, 2006**

Related U.S. Application Data

(62) Division of application No. 29/225,514, filed on Mar. 15, 2005.

(51) **LOC (8) Cl.** **21-02**

(57) **CLAIM**

We claim the ornamental design for an exercise device, as shown and described.

DESCRIPTION

FIG. 1 is an isometric view of an exercise device.

FIG. 2 is a front elevation view of the exercise device of FIG. 1.

FIG. 3 is a right side elevation view of the exercise device of FIG. 1.

FIG. 4 is a rear elevation view of the exercise device of FIG. 1.

FIG. 5 is a left side elevation view of the exercise device of FIG. 1.

FIG. 6 is a top plan view of the exercise device of FIG. 1; and,

FIG. 7 is a bottom plan view of the exercise device of FIG. 1.

The broken lines are for illustrative purposes only and form no part of the claimed design.

1 Claim, 7 Drawing Sheets
